No. 36,578.

Patented October 6, 1903.

UNITED STATES PATENT OFFICE.

ERNEST C. FOX, OF CLEVELAND, OHIO.

DESIGN FOR A REGISTER-PLATE.

SPECIFICATION forming part of Design No. 36,578, dated October 6, 1903.

Application filed August 5, 1903. Serial No. 168,384. Term of patent 3½ years.

To all whom it may concern:

Be it known that I, ERNEST C. FOX, a citizen of the United States, and a resident of Cleveland, county of Cuyahoga, State of Ohio, 5 have invented a new, original, and ornamental Design for a Register-Plate, of which the following is a specification, reference being had to the accompanying drawings, forming part thereof.

10 In the drawings, Figure 1 is a plan view of the plate, showing the new design. Fig. 2 is an end view thereof, and Fig. 3 is a side view thereof.

What I claim as new, and desire to secure by Letters Patent, is—

15 The ornamental design for a register-plate, as herein shown.

In testimony whereof I hereunto set my hand this 3d day of August, 1903.

ERNEST C. FOX.
